CONTROL CONSOLE FOR ILLUMINATION DEVICE

Robert I. Gross, Seneca, Mo., assignor to Eagle-Picher Industries, Inc., Cincinnati, Ohio, a corporation of Ohio

Filed June 14, 1968, Ser. No. 12,364

Term of patent 14 years

U.S. Cl. D26—13
Int. Cl. D26—99

FIG. 1

FIG. 2

FIG. 3

FIG. 4

FIG. 1 is a front perspective view of a control console for illumination device embodying my new design.

FIG. 2 is a rear perspective view thereof.

FIG. 3 is an elevational view in reduced scale taken from one side thereof, the opposite side being a mirror image of the side shown.

FIG. 4 is a bottom plan view thereof in reduced scale. The dominant features of my design reside in the portions shown in full lines.

I claim:

The ornamental design for a control console for illumination device, substantially as shown and described.
